UNITED STATES PATENT OFFICE.

RICHARD EAGER BOWEN, OF LOS ANGELES, CALIFORNIA.

RAILWAY-CROSSING.

1,381,787.

Specification of Letters Patent. Patented June 14, 1921.

Application filed June 4, 1920. Serial No. 386,616.

To all whom it may concern:

Be it known that I, RICHARD EAGER BOWEN, a citizen of the United States, and a resident of Los Angeles, in the county of 5 Los Angeles and State of California, have invented a new and Improved Railway-Crossing, of which the following is a description.

My invention relates to a railway crossing 10 and more particularly to a crossing in which provision is made for so forming the crossing tracks and wheel-flange grooves as to eliminate the bumping or pounding caused by the car wheels jumping across the 15 grooves formed in the respective tracks.

The nature of the invention, its distinctive features and advantages will clearly appear as the description proceeds.

Reference is to be had to the accompanying drawings it being understood that the drawings are merely illustrative of practical examples of the invention.

Figure 1 is a plan view of a railway crossing embodying my invention;

25 Fig. 2 is a vertical section on the line 2—2, Fig. 1;

Fig. 3 is a view similar to Fig. 2 but on the line 3—3, Fig. 1;

30 Fig. 4 is a plan view of an element employed at the intersection of the crossing grooves in the preferred form of my invention;

Fig. 5 is a plan view representing a form 35 of the invention in which all the parts are cast integral;

Fig. 6 is a vertical section on the line 6—6, Fig. 5.

Referring more particularly to Figs. 1 to 4, my improved crossing includes a base 9 40 on which the elements forming the various crossing track members are laid as follows:

Said base presents at the center a rectangular frame-like element 11 within the square formed by the intersecting tracks, 45 said frame being covered by a plate 10.

About said frame are disposed key members 12 having a wedge formation as best seen in section, Fig. 3. Outside of the main tracks at opposite sides of the central rectangular elements 10, 11, 12, I provide plates 50 13, 15, which may be the same size or different sizes and each surrounded respectively at three sides by frames 14, 14^a. The elements 12 at two sides of the central rectangle and the opposed side frames 14, 14^a define 55 the track grooves running in one direction and hereinafter referred to as relating to the

main track groove of the crossing. At those two sides of the central rectangular structure opposite the two frames 14, 15^a, I provide 60 plates 10^a each surrounded at three sides by a frame 11^a, at two sides of which frames 11^a the elements 12^a are employed, corresponding generally with and alining with the key elements 12 and defining one side of the continuations 16^a of the central track grooves 16 of the main rails. Parts of ordinary main track rails A are indicated as leading to the alined grooves 16, 16^a and to the tread surfaces of the main rails of the crossing as 70 hereinafter referred to.

Said main alined track grooves 16, 16^a of the crossing which are thus defined at one side by alined elements 12, 12^a are defined at their opposite sides by the aforementioned 75 three-sided frames 14, 14^a and the alining sides of triangular frames 14^b, said frames, 14, 14^a, 14^b, presenting the tread surfaces of the main rails of the crossing to receive the treads B of the car wheels while said alined 80 groove members 16, 16^a accommodate the flanges b of the wheels. In order that at the crossing the wheel treads B of the car wheels run at an elevation above and clear of the tread surfaces of the elements 14, 85 14^a, 14^b, the bottom surfaces of the grooves 16^a, 16 are at such an elevation relatively to the tread surfaces of the track elements that the wheels will run on their flanges b in said grooves. In the preferred form of the invention, I provide alined elements 17, 17^a, at the bottoms of the grooves 16, 16^a of the main tracks of the crossing and presenting 90 top surfaces on which the wheel flanges b run. The elements 17, 17^a are of hardened 95 steel to withstand the wear. Elements similar to the elements 17, 17^a are provided in the crossing grooves, the latter being designated at their central portions by the character 16^b and the continuations of the crossing grooves at the sides of the central portion 16^b being designated respectively 16^c, 100 16^d. The hardened elements in the crossing groove portions 16^b are indicated at 17^b and the alined hardened elements in the crossing 105 groove portions 16^c, 16^d are designated respectively 17^c, 17^d.

The tread surfaces of the crossing tracks are formed by the adjacent sides of the frame-like members 11^a with the alined 110 transverse members of the frames 14^b, said frames 11^a, 11^b defining one side of the crossing grooves 16^b, 16^c, 16^d. The opposite sides of said crossing grooves are defined by the

adjacent key elements 12 and the aligned transverse members of the frames 14, 14^a with their key elements 12^b, 12^c, the latter key elements alining with the adjacent key elements 12.

The plate 10 rests on inwardly directed flanges 18 on the frame-like element 11 and the plates 10^a on corresponding flanges 18^a on the frames 11^a while the plates 13, 15 10 rest on similar flanges 18^b on the plates 14, 14^a.

The wedge-shaped key or locking elements 12, 12^c are removably held in position by suitable means such as depending shanks 19 15 thereon threaded at their lower ends to receive nuts 20 beneath the base 9. The hardened bottom elements 17 to 17^a are received at one side in undercut recesses in the base and frame members as indicated at 26 in 20 Fig. 3 and the locking elements 12 to 12^c back up said bottom elements at the opposite sides and effectively prevent their displacement.

The distance between parallel grooves in 25 the crossing is such that in any side play of the car truck, the wheel flanges will bear against one or the other of parallel locking elements 12 so that said locking elements will take the wear of the side thrusts.

30 At the intersection of the main and crossing grooves I may as shown provide cruciform or equivalent elements 23 in the grooves flush with the hardened plates designated 17 to 17^a. Said elements 23 have depending shanks 24 threaded to receive nuts 25 and they may be lifted from their positions and turned about the axis of the shanks to dispose their arms differently according to the wear in a given direction thereon.

40 As seen in Fig. 2 the wheel flange grooves are of such a depth at the crossing that the wheel flanges will engage the hardened elements (17^b, 17^c, 17^d in said figure) and travel thereon as the wheels approach an intersection of the crossing grooves as well as in 45 passing through the crossing from one intersecting point of the grooves beyond the other, for which purpose the tread surfaces of the crossing to take the wheel treads B 50 are inclined so that a wheel approaching an intersecting groove of the crossing will travel on its tread surface downwardly toward the intersecting groove until the flange of the wheel rides on the hardened element at the 55 bottom of the groove before the wheel reaches an intersecting groove, the wheels correspondingly rolling over an incline upon leaving the crossing until the tread again rolls on its tread surface B.

60 In the form shown in Figs. 5 and 6 the whole crossing 9^a is formed in one piece to present parallel grooves 16^e for the wheels running in one direction and crossing grooves 16^f and said grooves have inclined 65 surfaces at the bottom thereof, said inclined

surfaces being designated 17^e for the first-mentioned grooves and 17^f for the crossing grooves so that as the wheels traveling in one groove and approaching an intersecting groove will, before passing said intersecting 70 groove, run with their flanges on said inclined surfaces at the near side of an intersecting groove, and across the latter and then run on the descending incline at the opposite side of the crossing causing the wheel tread B to eventually travel on the tread surfaces 75 11^d provided at the far ends of the grooves.

The hardened elements (17 to 17^d) are square in cross section and are adapted to be reversed end to end or be disposed with either side uppermost and thereby prolonging 80 the period of usefulness.

I would state in conclusion that while the illustrated examples constitute practical embodiments of my invention, I do not limit myself strictly to the mechanical details herein illustrated, since manifestly the same can be considerably varied without departure from the spirit of the invention as defined in the appended claims.

Having thus described my invention, I claim:—

1. A crossing presenting intersecting grooves for the wheel flanges, said crossing comprising a base presenting undercut recesses along one side of each groove, elements in the grooves at the bottom and extending into said recesses, and removable wedge-shaped locking elements for said first-mentioned elements at the opposite sides 95 from said recesses, the grooves at their intersections being of a depth to cause the wheel flanges to travel on the bottom surfaces of the grooves, the adjacent surfaces at the outer sides of the grooves being at 100 elevations to lie below the wheel treads.

2. A railway crossing presenting intersecting grooves for the wheel flanges, and hardened wedge shaped elements along the grooves at the inner sides to take the side 110 thrusts of the wheel flanges, the grooves at their intersections being of a depth to cause the wheel flanges to travel on the bottom surfaces of the grooves, the adjacent surfaces at the outer sides of the grooves being 115 at elevations to lie below the wheel treads.

3. A railway crossing presenting intersecting grooves, the grooves at their intersections being of a depth to cause the wheel flanges to travel on the bottom surfaces of the grooves, the adjacent surfaces at the outer sides of the grooves being at elevations to lie below the wheel treads, there being 120 elements forming the bottoms of the grooves and presenting a plurality of faces, said elements being removably held to permit of their being positioned with either of said 125 faces uppermost.
